GREGORY E. SAWYER, OF INDEPENDENCE, KANSAS

SUCKER-ROD ELEVATOR

Application filed March 15, 1928. Serial No. 261,917.

My invention relates to sucker rod elevators.

In accordance with my invention, a sucker rod elevator is produced, embodying a body portion having a recess or opening to receive the sucker rod. The sucker rod is held within the recess by means of a latch element or latch elements, movable across the recess or opening. The body portion is pivotally suspended from actuating members, in turn supported by a bail or the like. Means are provided whereby the latch element or elements are automatically moved inwardly when the supporting actuating members are swung to an upstanding position with relation to the body portion. When the supporting actuating members are thus shifted to the upstanding position, they are automatically locked against further turning movement with relation to the body portion. The device is strong, durable, and easy to operate.

In the accompanying drawings forming a part of this specification and in which like numerals are employed to designate like parts throughout the same,

Figure 1 is a side elevation of a sucker rod elevator embodying my invention;

Figure 2 is a similar view of the rear side of the device, the bail being broken away;

Figure 3 is an end elevation of the device, the bail being broken away;

Figure 4 is a plan view of the device showing the supporting actuating members shifted to the horizontal position;

Figure 5 is a similar view, with the supporting actuating members shifted to the vertical position;

Figure 6 is a transverse section taken on line 6-6 of Fig. 5;

Figure 7 is a bottom plan view of the device, with the supporting actuating members in the horizontal position;

Figure 8 is a transverse section taken on line 8-8 of Fig. 5; and

Figure 9 is a vertical section taken on line 9-9 of Fig. 5.

In the drawings, wherein, for the purpose of illustration, is shown a preferred embodiment of my invention, the numeral 10 designates the body portion of the sucker rod ele-

vator, which remains generally horizontal, in use. This body portion is provided with an opening or recess 11, for the reception of the sucker rod, providing jaws 12, which are preferably rounded at 13. Preferably formed integral with the opposite sides of the body portion 10 are trunnions 14, as shown.

The numeral 15 designates a pair of supporting actuating members, embodying sleeves 16, carrying pairs of spaced knuckles 17. These sleeves are pivoted upon the trunnions 14, and are held thereon by pins 18 or the like.

Coacting with the supporting actuating members 15 is a bail 19 provided at its lower end with eyes 20, arranged between the knuckles 17, and pivoted thereto by pins 21 or the like.

Each sleeve 16 is provided upon its inner side with a recess 22, extending through the inner side thereof and affording an inclined cam face 23, and also providing end stop walls 24 and 25. The jaws 12 are provided near their outer ends with transverse openings 26, receiving sliding latch elements or bolts 27, having heads 28. These latch elements are automatically shifted outwardly by means of compressible coil springs 29. The outer ends of the latch elements or bolts 27 and their heads 28 project into the recesses 22, and the heads 28 engage the cam faces 23, and these heads engage the end stop wall 25 when the supporting actuating members are shifted to the horizontal position with relation to the body portion 10 and engage the end stop walls 24, when the members 15 are shifted to the relative vertical position, thus limiting the extent of swinging movement of such members 15.

Means are provided to lock the supporting actuating members 15 to the body portion 14, against swinging movement, when they are shifted to the upper vertical position, with relation thereto. This locking means embodies a pair of locking bolts or elements 30, slidably within recesses 31, formed in lateral extensions 32, of the sleeves 16. The locking bolts 30 are urged outwardly by compressible coil springs 33. When projected, the locking bolts 30 enter recesses 34, formed

in the rear end or face of the body portion 10. The outer ends of the locking bolts 30 are arranged to be engaged by a retracting element or lever 35, pivoted to the body portion 10, as shown at 36, and having cam ends 37, to engage with the locking bolts. A knob 38 is attached to the retracting element 35 to manipulate the same. The retracting element 35 is positioned between horizontal flanges 39, formed upon the rear end of the body portion 10, at the top and bottom thereof.

The operation of the elevator is as follows: When the supporting actuating members 15 are shifted to the relative horizontal position, the stop end walls 25 engage the heads 28 of the latch elements 27, and these latch elements are automatically shifted to the outer position, by means of the springs 29. The sucker rod may now pass into the recess 11. The supporting actuating members 15 are now shifted to the relative vertical position, extending above the body portion 10, whereby the latch elements 27 are projected into the recess 11, to retain the sucker rod therein.

The heads 28 now engage the end stop walls 24. At this time, the locking bolts 37 are projected into the recesses 34, by the springs 33, and hence the members 15 are locked to the body portion 10, against turning movement, in either direction, by the end stop walls 24 and the locking bolts 37. By swinging the retracting element 35 upon its pivot, the locking bolts 37 may be retracted, and the members 15 shifted to the relative horizontal position, as explained.

It is to be understood that the form of my invention herewith shown and described is to be taken as a preferred example of the same, and that various changes in the shape, size and arrangement of parts may be resorted to, without departing from the spirit of my invention, or the scope of the subjoined claims.

Having thus described my invention, I claim:

1. A sucker rod elevator comprising, a body portion having a recess to receive the sucker rod, latch elements carried by the body portion and adapted to be projected into the recess, supporting actuating members pivoted upon the body portion and having cam faces to engage with the latch elements to project them, a support connected with the supporting actuating members, and means to lock the supporting actuating members to the body portion against turning movement, said means including spring pressed bolts carried by the actuating members.

2. A sucker rod elevator comprising, a body portion having a recess to receive the sucker rod, latch elements carried by the body portion and adapted to be projected into the recess, supporting actuating members pivoted upon the body portion and having cam faces to engage with the latch elements to project

them, a bail connected with the supporting actuating members, locking bolts carried by said members and adapted to engage with the body portion, and means to project the locking bolts.

3. A sucker rod elevator comprising, a body portion having a recess, latch elements carried by the body portion to project into the recess, supporting actuating members pivoted upon the body portion and having cam faces to engage the latch elements, supporting means connected with said members, locking bolts carried by said members and adapted to engage with the body portion, means to project the locking bolts, and a retracting element carried by the body portion to engage said locking bolts.

4. A sucker rod elevator comprising, a body portion having a recess, latch elements carried by the body portion to project into the recess, supporting actuating members pivoted upon the body portion and having cam faces to engage the latch elements and project them and also having end stop walls to engage with the latch elements, supporting means connected with said members, locking bolts carried by the members to engage with the body portion, said locking bolts and end stop walls being adapted to lock said members to the body portion against swinging movement in opposite directions, means to project the locking bolts, and a retracting element carried by the body portion to engage with the locking bolts.

5. A sucker rod elevator comprising, a body portion having a sucker rod receiving recess formed through one end thereof and locking bolt receiving recesses in the opposite end, sliding latch elements carried by the body portion to project into the sucker rod receiving recess, springs to retract said latch elements, supporting actuating members pivoted upon the body portion and having recesses receiving the outer ends of the latch elements, said recesses providing cam faces and end stop walls, sliding locking bolts carried by said members and adapted to be projected into the bolt receiving recesses, springs to project the locking bolts, and a member pivoted to the body portion to engage the locking bolts and retract them.

6. A sucker rod elevator comprising, a body portion having a recess to receive the sucker rod, sliding latch elements carried by the body portion and adapted to be projected into the recess, supporting actuating members pivoted upon the body portion and having openings formed therein, said openings providing cam faces and end stop walls, the end stop walls coacting with the latch elements to limit the swinging movement of said members in one direction with relation to the body portion, releasable means carried by the supporting actuating members to limit the swinging movement of said members in

an opposite direction with relation to said body portion, and supporting means connected with said members.

7. A sucker rod elevator comprising, a body portion having a recess to receive the sucker rod, a latch element carried by the body portion and adapted to be projected into the recess, supporting actuating members pivoted upon the body portion, one member having a cam face to engage with the latch element to project the same, a sliding bolt carried by one supporting actuating member, and means whereby the sliding bolt is projected into locking engagement with the body portion when its member is shifted to a selected position with relation to the body portion.

8. A sucker rod elevator comprising, a body portion having a recess to receive the sucker rod, a latch element carried by the body portion and adapted to be projected into the recess, supporting actuating members pivoted upon the body portion, one member having a cam face to engage with the latch element to project the same, means to lock one actuating supporting member to the body portion against turning movement in one direction, when such supporting member is swung to a selected position with relation to the body portion, and a bail pivotally connected with the supporting actuating members so that they may be readily swung with relation to the bail.

9. A sucker rod elevator comprising a body portion having a recess to receive the sucker rod, slideable latch elements carried by the body portion and adapted to be projected into the recess, supporting actuating members pivoted upon the body portion and having cam faces to engage with the latch elements to project the same and end stop walls to engage with the latch elements to limit the swinging movement of the supporting actuating members in one direction with relation to the body portion, and releasable locking means thrown into action when the latch elements engage with the end stop walls to lock one supporting actuating member to the body portion against swinging movement in an opposite direction.

10. A sucker rod elevator comprising a body portion having a recess to receive the sucker rod, latch elements carried by the body portion and adapted to be projected into the recesses, supporting actuating members pivoted upon the body portion and having cam faces to engage with the latch elements to project them, a support connected with the supporting actuating members, and means to lock one supporting actuating member to the body portion against turning movement, said means including a reciprocating element extending transversely of one of the supporting actuating members.

In testimony whereof I affix my signature.
GREGORY E. SAWYER.
